UNITED STATES PATENT OFFICE.

MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,173,775.

Specification of Letters Patent. Patented Feb. 29, 1916.

Application filed July 17, 1913. Serial No. 779,479.

To all whom it may concern:

Be it known that I, MORTON L. JOHNSON, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of

10 this specification.

My invention relates to telephone exchange systems employing call receiving operators and connecting operators and finds a very important embodiment in those systems 15 wherein connections made between calling and called lines are individually charged for, the connections of calling lines with called lines being effected in part by means of call receiving or recording operators and toll board or connecting operators.

The invention will be specifically described in connection with a toll system in which the call receiving operators act as recording operators and the toll operators act 25 as connecting operators, though the invention is not to be limited to such employment.

My invention has for one of its objects the provision of means whereby recording operators may select idle toll board operators to effect an automatic distribution 30 suited to the capacity of the latter operators.

The invention has for another of its objects the provision of means for establishing communication between the recording operators and the toll board operators which includes recording instruments at the toll board and transmitting instruments at the recording operators' positions. In the preferred embodiment of the invention these receiving instruments are desirably telautograph receivers and the transmitting instruments are, then of course, telautograph transmitters, though the invention in all of its embodiments is not to be limited to the

40 nature of the receivers at the toll board and the transmitters at the recording operators' positions. By means of this feature of the invention the nature of the connection to be established is placed in record form before 45 the selected toll board operator. Where telautographic instruments are employed the form of record is permanent and may be

transmitted to a filing clerk after the connection has been concluded or abandoned.

The invention has for another of its objects the provision of means whereby the recording operator may have access to an information operator to supply that information which the calling subscriber may happen to lack, such for example as the telephone number of the wanted party.

The invention has for its further object the provision of information operators who are provided with equipment for furnishing the calling subscribers with information as to the status of desired connections without the necessity of interrupting the work of the toll board operators for this purpose and in order that these information operators may be fully equipped to answer the queries of calling subscribers at any stage of the desired connections the recording instruments are located within reach of the information operators so that they may have the same information which the recording operators furnished to the toll board operators. Inasmuch as recording instruments in the form of telautograph receivers are preferably employed the information operators are provided with telautograph receivers. These telautograph receivers are desirably 75 provided over by the filing clerk, the information operators getting their information from the record furnished by these latter telautograph receivers and filed within 80 reach of the information operators by the filing clerk.

I will explain my invention more fully by reference to the accompanying drawings showing the preferred embodiment thereof and in which—

Figure 1 is a general diagrammatic view illustrating the invention; Figs. 2, 3 and 4 are views, which taken collectively, illustrate the preferred embodiment of the invention more in detail; and Fig. 5 illustrates the manner in which Figs. 2, 3 and 4 are assembled when they are to be read in connection with each other.

Like parts are indicated by similar characters of reference throughout the different figures.

Referring first more particularly to Fig. 1, I have there shown telephone lines ex-

tending from telephone stations 200, 201 to an exchange where an A operator is provided with link connectors 1 for connecting jacks 2 pertaining to the lines of stations 5 200, 201 with jacks 3 pertaining to trunk lines 4 which terminate in spring jacks 5 in the presence of call receiving operators acting as recording operators. These recording operators are provided with link connectors 10 6 having plugs which may be inserted in the jacks 5 to enable the recording operators to converse with the calling subscribers at the stations 200, 201, the A operators switching the calling lines into connection with recording operators when such calling lines desire 15 long distance or toll connection. If the calling lines desire local connections the mates of the plugs that are inserted in the jacks 2 of the calling lines are inserted in corresponding 20 jacks of the called lines, as the system happens to be here illustrated. The recording operator in connection with a calling line will ascertain the usual information which is required as a condition precedent 25 to the establishment of a long distance or toll connection such as the name and telephone number of the calling party and the name, telephone number and address of the wanted party. While receiving this information 30 the operator will depress a key 7 corresponding to the division of the toll board where access may be had to the desired line, whereupon a selector switch 8 individual to the depressed key is set into 35 operation by the closure of a switch 9 common to the recording operator's position. The operated selector switch selects an idle telautograph receiver 10 located in the presence of an idle operator at the division of 40 the board where access may be had to the desired line. An idle telautograph receiver having been selected the operator will write the information which she has received by means of a telautograph transmitter 11, the 45 recorded information being written upon the selected telautograph receiver 10 and upon a telautograph receiver 12 located in the presence of the recording operator so that she may check up the work of her telautograph 50 transmitter. After this message has been transmitted to the toll or connecting operator the recording operator instructs the calling subscriber to hang his telephone upon its switch hook whereupon the equipment of 55 the calling line is restored to normal upon the withdrawal of the plug by the A operator that united the calling line with the recording operator. The toll board operator having the selected telautograph receiver 60 will put up the connection between the calling line and the wanted line in any usual or suitable manner, as for example by means of cord circuits 13 which may connect jacks 14 belonging to toll trunks 15 with jacks 16 65 pertaining to the lines 17 extending to the distant exchange 18 to which the line wanted by the calling subscriber extends; the toll trunks 15 terminating in plugs 19 at a B toll operator's position where such B toll operator connects the trunk 15 assigned by 70 her to the toll operator with the calling line. While I have illustrated the telephone lines 17 as extending between the toll board and exchange 18, yet it is obvious that these telephone lines 17 may, in certain systems, extend directly to subscribers' stations. The toll board is shown as being located in the same place with the exchange to which the lines of the stations 200, 201 extend. The final connection with the calling line by the 75 plug 19 is not effected until the desired party has been secured and is ready to converse. After conversation between the parties has been completed and the connection taken down, the toll board operator will deposit 80 the record slip in a pneumatic tube conveyer 20 which conveys the slip to a filing clerk located at 21. If the calling subscriber is not able to furnish the recording operator with all of the information desired, such for 85 example as the exact telephone number of the wanted party, the recording operator, after having secured all the information possible from the calling subscriber, will depress the employed key 7 beyond its normal 90 range of movement to secure connection with an information operator having telephone equipment 22. If there is more than one information operator an idle information operator is selected by means of an idle 95 operator selector switch 23 which, in conjunction with the switch 24, closed upon the extraordinary movement of the employed key 7, will connect an idle operator with the telephone outfit 25 of the recording operator. The switch 24 also operates to set the selector switch 23 into motion. Having secured connection with the idle information operator the recording operator will complete 100 the ticket at her transmitter 11 whereupon the operations will proceed as hitherto described, though this feature of the invention is not to be limited to the method by which the information acquired by the recording operator from the information operator is transmitted to the toll operator. When the operator manipulates the key 105 9 she throws a telautograph receiver 26 into circuit with her telautograph transmitter 11 so that the message produced at 110 10 is duplicated at 26 in the presence of a filing clerk at 21 who files the record made by the receiver 26, later filing with such record the corresponding record received through the conveying tube 20. If the calling subscriber should wish to ascertain the condition of the desired connection he is connected with a trunk line 27 by means of a link 6 and jacks 5 and 28, this trunk line 115 leading to information operators, an idle one 120 125 130

of whom will depress a key 29 to include her telephone in circuit with the calling line, the information operator using the files of the filing clerk for the purpose of gathering 5 information to furnish to the calling subscriber.

By means of the system thus generally outlined in connection with Fig. 1 it will be seen that the tool board operators are 10 relieved of the burden of at any time supplying information to the calling subscriber so that such operators may work to their full capacity in putting up connections. This aspect of the invention is not to be 15 limited to the presence of recording instruments at the recording and toll board positions. Efficiency of the tool board operators is obviously increased by means of that feature of the invention wherein the orders are 20 automatically transmitted to idle operators by means of apparatus controlled by the recording operators. While I have shown the equipment 1 of a receiving operator and the equipment of an added recording op- 25 erator and while the lines directly accessible to the receiving operator do not extend directly to the toll board, I do not wish to be limited to these characteristics.

Referring now more particularly to Figs. 30 2, 3 and 4 I will describe the preferred embodiment of my invention more in detail. The subscribers' substations 200 and A300 are provided with telephone lines which extend respectively to the positions of the link 35 connectors 1 and 13. The equipment at station 200 includes a telephone receiver 30, a telephone transmitter 31, a call bell 32, condenser 33, and a switch hook 34 provided with a normal contact for including the bell 40 and condenser in bridge of its line and an alternate contact for including the telephone receiver and transmitter in bridge of its line. The equipment at station A300 is similar to that at station 200 excepting that 45 the condenser and lower switch hook contact are absent. Each of the telephone lines is illustrated as being equipped with line signals 35 controlled by any suitable line equipment so well known by those skilled 50 in the art as to require no description. The connecting outfits 1 and 13 may be of any usual or suitable form, those shown being in the form of cord circuits terminating in plugs at both ends and as the cord circuits 55 illustrated are of well known arrangement they will not be particularly described. When a call is received at the exchange where the link connectors 1 are located, the operator there will insert the answering 60 plug 36 into the jack 2 of the calling line and will ascertain the connection desired by the calling subscriber after the listening key 27 has cut such operator's telephone in circuit with the calling line. Assuming that 65 the connection is for some such station as

A300 the operator will insert the connecting plug 37 in the jack 3 pertaining to some idle trunk 4 extending to the second call receiving, or recording, operator's position where such second call receiving operator is 70 provided with link connectors 6. After the plug 37 has been inserted in the jack 3 of an idle trunk 4 an apparent and well known circuit is established for the relay 38 whose armature in turn closes an apparent circuit 75 for a signaling device 39 located in the presence of the second call receiving operator, and if there be a number of such operators the signaling device 39 in the presence of each of such operators has its circuit closed 80 by said relay 38. Some second call receiving operator, or as she will hereinafter be termed recording operator, will answer her signal 39 by inserting the plug 40 of an idle cord circuit 6 in the jack 5 pertaining to the 85 trunk 4 now connected with the employed plug 37. The heel of the plug 40 establishes an apparent circuit for the lower coil of relay 41, the armature switch of this relay thereupon effacing the signal at each 90 signal device 39, this armature switch also thereupon establishing an apparent locking circuit for the relay 41 by way of the alternate contact of such armature to prevent reoperation of the signals 39 until the plug 95 37 has been withdrawn and reinserted.

Each link 6 includes well known supervisory relays 42 and 43 which need not be described. Each such link also includes a well known listening key 44 for including 100 the associate operator's telephone equipment 25 in telephonic association with the employed link 6. The recording operator will depress her key 44 to receive from the calling subscriber the number of the call or connection desired and as she ascertains this information she depresses her key 7 pertaining to that connecting or toll board operator's position or positions at which the desired line is accessible. As the invention 110 is herein embodied there is a telautograph receiver 10 at each toll operator's position which is connected with the recording operator's equipment when such toll position is thus connected with such equipment. Where 115 there is a number of toll operators there is also a number of telautograph receivers 10 and a selector switch 8 is employed for selecting a receiver 10 and the operator having charge thereof that are not otherwise 120 employed. This selector switch 8 is set in motion upon the depression of the key 9, the left hand pair of contacts of this key closing a circuit traceable from ground, said contact, the bottom armature switch of relay 45, the normal contact of this armature switch, the motor magnet 46 of the employed selector switch 8, sluggishly operating relay 47 and its armature and contact, to the grounded common battery 48. The wipers 125 130

of the employed selector switch are now set into motion until the wiper 50 of this switch encounters a grounded contact whereupon a circuit is established traceable from the 5 grounded battery 48, the relay 45, the armature of motor magnet 46 and its contact, the extreme left hand pair of contacts of the employed switch 7, the wiper 50, the contact engaged thereby, the armature switch 10 of relay 51 in its idle position (such being the case when the link pertaining to this relay 51 is idle), the contact of this armature switch, the armature switch of relay 52 and its contact, to ground. A locking 15 circuit is established for relay 45 traceable from the left hand pair of contacts of the employed switch 9, the lowermost armature switch of relay 45 and its left hand alternate contact, the winding of relay 45, the 20 grounded battery 48, to ground. A circuit is established for relay 51 traceable from the left hand pair of contacts of the employed key 9, the bottom armature switch of relay 45 and its right hand alternate contact, the second pair of contacts from the 25 left of the employed switch 7, the wiper 53 of the employed switch 8, the relay 51, to the grounded battery 48. When the relay 51 is thus energized, ground is removed 30 from the waiting contact engaged by the wiper 50 at the armature of this relay whereby other switches 8 will not select the same links or trunks which have been selected by the employed switch 8, it being 35 understood that the switches 8 of a group whose contacts are similarly positioned have such contacts in multiple connection. When the switch 8 has been brought to rest an idle telautograph receiver 10 is, by means of 40 such switch, connected with the telautograph transmitter 11 belonging to the corresponding recording operator. Upon the depression of the key 9 the telautograph receiver 26 in the presence of the 45 filing clerk was also connected with the telautograph transmitter 11.

I have deemed it unnecessary to illustrate and describe in detail the means by which a message written by the recording operator upon the telautograph transmitter 11 is reproduced at the telautograph receivers 10 and 26 as such equipment is so well known by those skilled in the art. The prior art respecting telautographs is exhibited by United States Patent 656,828, issued August 28, 1900 and Patents 668,889 to 668,895 inclusive, dated February 26, 1901. It will suffice to say that current for operating the telautograph receiver 10 is 55 transmitted over a metallic circuit traceable from the lower side of the transmitter 11, the contact 54 of the employed key 9, the contact to the right of contact 54, the top armature switch of relay 45 and its contact, the right hand pair of contacts of the 60

employed key 7, the wiper 55 of the employed switch 8, the selected telautograph receiver 10, the wiper 56, the contacts 57 of the employed key 7, the intermediate armature switch of the relay 45 and its contact, the pair of contacts at 58 to the telautograph transmitter 11. The circuit for the telautograph receiver 26 is apparent. At the recording operator's position a telautograph receiver 12 is in parallel with the 75 receivers 10 and 26 so that the recording operator will check the message which she is transmitting to the receivers 10 and 26.

The calling subscriber ordinarily is able to furnish the recording operator with all 80 the information desired such as the number of the calling line and the complete telephonic and geographic designation of the desired line. It sometimes happens that the calling subscriber is not able to furnish the 85 complete data respecting the desired line and in such event the employed key 7 is further depressed to establish a circuit at 24 to set a selector switch 23 into operation for the purpose of selecting an idle information 90 operator, the circuit established at 24 being traceable from ground, the contacts of switch 24, the bottom armature switch of relay 59, and its normal contact, the motor magnet 60 of the selector switch 23, the sluggishly 95 operating interrupter relay 61 and its armature switch and contact, to the grounded battery 48. The motor magnet 60 continues in operation until the wiper 62 of the selector switch 23 encounters a grounded waiting 100 contact whereupon a circuit is established traceable from the grounded battery 48, the winding of relay 59, the armature of motor magnet 60 and its contact, the wiper 62 and its engaged waiting contact, 105 the armature switch of relay 63 and its engaged contact (a relay 63 being individual to each information operator and being de-energized when the trunk line leading to such operator is idle), the armature switch 110 of relay 64 and its engaged contact, to ground. An apparent locking circuit is thereupon established for the relay 59 by way of the left hand alternate contact of the bottom armature switch of this relay 115 and the closed switch 24, the recording operator maintaining the key 7 in its fully depressed position until she has finished her conversation with the selected information operator. A circuit is established at the bottom armature switch of relay 59 traceable from the switch 24, this bottom armature switch, the left hand alternate contact of this switch, the relay 65, to the grounded battery 48. Relay 65 will now attract its 120 armature switches to exclude the telephone equipment 25 of the recording operator from connection with the calling line if the recording operator has not previously released her listening key 44 for this purpose to avoid 125 130

confusion which might arise if the calling party were at liberty to listen into the conversation between the recording operator and the information operator. The recording operator's telephone equipment 25 is now included in circuit with the primary repeating coils 66, this connection being established by way of the armature switches of relay 65 and their alternate contacts, the two upper switches of the relay 59 and their contacts, and the wipers 67 and 68 of the employed switch 23 and the waiting contacts constituting terminals of the bridge including the coils 66. The coils 66 are in inducing relation to the secondary coils 69 which in turn are in local circuit with the head telephone at 22 of the selected information operator.

The information operators are provided with the usual telephonic equipment whereby they may impress telephonic current upon the telephone equipment 25 of the recording operator. An obvious circuit is now established that includes impedance coils at 70 which are in closed circuit with the coils 66 whereby the relay 63 in this closed circuit is energized to remove the ground from the contact engaged by the wiper 62 so that no other selector switch 23 may select the previously selected equipment 22, it being understood that similarly positioned contacts of selector switches 23 in the same group are in multiple connection. The recording operator will write the information upon her transmitter 11 as she receives it either from the calling subscriber or both from the calling subscriber and selected information operator and if a part of this information has been received from an information operator the recording operator will allow the key 7 to be restored to its first depressed position to open the switch at 24 after the necessary information has been secured from the information operator whereby the relays 59 and 65 are deenergized to restore the equipment of the employed switch 23 to an idle condition, the relay 63 obviously being again deenergized to permit the associate telephone equipment 22 again to be selected. When the recording operator has transmitted to the toll operator all the information necessary to enable the toll operator to put up the connection, the recording operator will release the key 9 whereby circuits for the relays 45 and 51 are opened to restore the equipment of the employed selector switch 8 to an idle condition. At this time the recording operator will inform the calling subscriber at 200 to restore his telephone receiver upon its switch hook and the recording operator will withdraw the plug 40 whereafter the first operator will withdraw the plugs 36 and 37 from their jacks whereby all of this equipment is restored to normal. The filing clerk

having charge of the telautograph receiver 26 will tear off the information slip and file it within access of the information operators having the telephone equipments 22. The toll operator will also tear off the slip upon 70 which the recorded information appears but will hold this slip in readiness to add thereto other information such as the duration of the conversation between the connected parties and any other data that may be 75 required in connection with toll service. The toll operator will thereupon seek connection with the operator having charge of plugs at 19 at the board to which the calling line extends, a usual order wire circuit 71 80 answering this purpose. The operator at 19 will assign to the toll operator an idle plug 19, which will be inserted in the jack of the calling line 200 in accordance with instructions to this effect sent to the toll 85 operator by way of the order wire 71. The toll operator will thereupon insert the plug 72 of an idle cord circuit 13 into the jack 14 individual to the employed plug 19 and will insert the mate 73 of the plug 72 within 90 the jack 16 pertaining to a desired line A300. The calling and called parties are now signaled upon the manipulation of the ringing keys 74 and 75 in the usual way. The cord circuit at 13 is of any usual or 95 suitable construction and arrangement, that shown being so well known by those skilled in the art as to require no description. After the parties have finished their conversation or in the event of failure to secure 100 connection between the parties the toll operator will fill out the ticket giving the necessary data and will transmit it by the pneumatic tube conveyer 20 to the filing clerk having charge of the telautograph receiver 26, and this filing clerk will file this second ticket with the ticket which she previously filed so that both tickets are accessible to the information operators.

When a toll operator is putting up a connection either her listening key 76 pertaining to the employed link 13 or her order wire key 77 is in a depressed position whereby the relay 52 is then energized to remove ground from the waiting contact engaged 115 by the wiper 50 so as to guard the selected telautograph receiver 10 from selection by another switch 8 while the toll operator is still engaged with the desired connection. If the calling subscriber should desire any 120 information respecting the progress of the desired connection the recording operator will switch such subscriber into connection with the information operators having the telephone equipments 22, one of these operators depressing a key 29 for the purpose of including her telephone set in circuit with the calling line. The recording operator may establish this connection between the calling line and the information operators 125 130

6

by means of a plug 78 (companion to the plug 40 that is connected with the calling line in the manner previously described) inserted in the jack 28 connected with the 5 information operators' positions, there being signaling apparatus 80 at the information operators' positions individual to each trunk jack 28, each trunk line 27 having as many signal lamps 80 as there are 10 information operators' positions, one lamp at each position. As was hitherto stated the filing clerk files her record slips where they are accessible to the information operators whereby the information operators may 15 readily supply the calling subscribers with information, the recording and toll operators being relieved of this burden.

While I have herein shown and particularly described the preferred embodiment of 20 my invention I do not wish to be limited to the precise details of construction and circuit arrangement shown as changes may readily be made without departing from the spirit of my invention, but

Having thus described my invention I 25 claim as new and desire to secure by Letters Patent the following:—

A telephone exchange system including telephone lines extending to an exchange; call receiving operator's equipment having 30 means for associating it with calling lines; connecting operators' equipments to which telephone lines extend, these equipments including recording receivers; a transmitter at the call receiving operator's position for 35 operating the recording receivers; a selector switch for selecting an idle recording receiver; and an additional recording receiver located in the presence of a third operator and operable by the transmitter 40 of the call receiving operator.

In witness whereof, I hereunto subscribe my name this fourteenth day of July, A. D., 1913.

MORTON L. JOHNSON.
